UNITED STATES PATENT OFFICE

FRED BALL, OF SPOKANE, WASHINGTON

DRIFT VALVE

Application filed May 22, 1926. Serial No. 111,004.

My present invention relates to improvements in drift valves designed especially for use upon railway steam locomotives as an auxiliary appliance for admitting to the cylinders and valve chambers a supply of steam for lubricating and maintaining the parts in heated condition when the normal supply of steam to the cylinders is cut off. As is well known, during the time the locomotive is drifting or coasting with the main steam supply cut off, the absence of the steam permits the parts to become dry and the admission of air to the interior parts of the cylinders and chambers cools the walls, thus creating an undesirable condition and impairing the efficiency of the locomotive. The primary object of my invention is the provision of an appliance for supplying an auxiliary supply of steam, continuously operating at and above a minimum speed (say seven miles per hour) of the locomotive, in order that the main steam supply may be cut off when desirable, and yet maintain the cylinders, chambers and operating parts in working condition for greatest efficiency. The appliance is applicable for use in connection with locomotives now in use without necessity for material change, and is operated, preferably from one of the drive wheel axles through a speed governor, as will hereinafter be more fully pointed out and claimed.

In the accompanying drawings I have illustrated one complete example of the physical embodiment of my invention wherein the parts are combined and arranged according to the best mode I have thus far devised for the practical application of the principles of my invention.

Figure 1 is a diagrammatic view of a railway steam locomotive having the appliance of my invention installed thereon, and indicating the arrangement and assembly of parts.

Figure 2 is a top plan view of the appliance.

Figure 3 is a vertical sectional view with the drift valve in closed position.

Figure 4 is a view in side elevation of the appliance.

Figure 5 is a transverse sectional view at line 5—5 of Figure 3.

In order that the general arrangement and relation of parts may readily be understood I have indicated in Figure 1 the parts to be lubricated and heated as a cylinder 1 and steam chest 2, with the usual operating piston and valves therein, to which the steam for operating the engine is supplied through the main steam line or pipe 3. The usual turret or fountain 4 for auxiliary purposes is located in the cab of the locomotive and the auxiliary supply of steam for the appliance is taken therefrom through the pipe 5 to the cylinder casing 6, and the lubricating pipe 7 is connected at a suitable place to the main supply pipe 3 to conduct steam to the chest and cylinder when the main supply is cut off as well as during the time that the locomotive is traveling above a minimum speed.

Within the cylinder casing 6, which is disposed vertically and located adjacent the steam cylinder 1, is provided an annular steam chamber 8 having an outlet port 9 to which the lubricating pipe 7 is connected. The auxiliary supply pipe 5 is connected to a port 10 in the top head of the cylinder casing and opens to an inner steam cylinder 11 projecting downwardly in the cylinder casing 6. The inner cylinder is fashioned with a closed lower end or head and near its closed head is fashioned with a number of radial ports 12, normally closed by the slide valve 13 but adapted to register with complementary ports 14 of the slide valve when the speed of the locomotive reaches or exceeds a predetermined speed, as seven miles per hour, in order to render the appliance operative. The cylinder casing and slide valve are supported upon a yoke 15 and a flanged head 16 is interposed between the yoke and the cylinder casing with fastening bolts for rigidly securing the parts together. The yoke is fashioned with a base plate 17 for attaching to a suitable supporting member of the engine frame and the appliance is supported in vertical position as indicated in Figures 1 and 3. The slide valve as shown is of cylindrical form with an open upper end and is guided at its exterior by the walls of the lower reduced portion of the cylinder casing and at

its interior side by the inner steam cylinder 11.

The valve stem 18 is rigidly secured to the lower head of the valve as by screw threads and is provided with a stuffing box or slide bearing 19 in the cylinder head 16 or plate interposed between the yoke and cylinder casing. Small drain ports 20 and 21 are provided in the head 16 and the valve head respectively to drain excess steam and maintain an equalized pressure in the hollow piston and cylinder casing.

As shown in Figure 3 the drift valve is closed, but it is opened by the action of a centrifugal type of speed governor indicated as a whole by the numerals 22 and connecting the valve stem 18 with the complementary, telescoping, tubular shaft 22' of the governor, which shaft is journaled at 24 on the attaching or base plate 17.

A bevel pinion 25 on the tubular shaft 23 and a complementary pinion 26 on the pulley-shaft 27 journaled in bearings of the yoke 15 transmit motion from the pulley shaft to the actuating part of the governor to extend the balls, pull down the stem and its drift valve and cause the ports 14 and 12 to register.

A pulley 28 is carried on the pulley-shaft 27 and a belt 29 from the drive pulley 30 (dotted lines Figure 1) on an axle of the locomotive is used to operate the governor at and above a minimum speed to be predetermined.

When the drift valve is lowered to cause the ports 14 and 12 to register it will be apparent that steam entering the annular steam space 8 through the port 9 from pipe 5, passes through the registering ports to the interior of the inner cylinder 11, thence upwardly through the outlet port 10 and pipe 7 to the main steam pipe 3. While the locomotive is traveling at the predetermined minimum speed or at a speed in excess of this minimum speed the valve is retained in open position. As the speed of the locomotive increases the valve stem is drawn down into the tubular governor shaft 23, which is provided with a drain port 23' to permit exit of water or other extraneous matter, and a bearing ball 31 is also located at the lower end of the tubular portion of the shaft 23 to perform the functions of a thrust bearing for the lower end of the stem 18 when the governor reaches high speed.

Thus with the appliance supplying a continuous and automatically controlled auxiliary quantity of steam to the main steam pipes and cylinders and other parts of the operating mechanism of the locomotive, as described, the locomotive may be permitted to drift or coast when the main supply of steam is cut off, and the parts are lubricated and maintained at normal working condition in order that the main supply of steam when

again applied may immediately become effective for efficient use.

When the speed of the locomotive falls below the predetermined minimum rate the weight of the governor balls and the weight of the piston, under gravity action, automatically cause the drift valve to rise or ascend, closing the complementary ports 12 and 14 to shut off the auxiliary supply of steam.

Having thus fully described my invention, what I claim as new and desire to secure by Letters Patent is—

The combination with a closed cylinder casing having a radial inlet port, of an inner cylinder forming an annular space within the casing, said inner cylinder having an end port and a radial port, a cylindrical valve reciprocable in said space, said valve having one closed end and a radial port, the latter for coaction with the complementary port of the cylinder, a stem at the closed end of the valve, and a governor mechanism connected with the stem for operating the valve.

In testimony whereof I affix my signature.

FRED BALL.
